U.S. PATENT DOCUMENTS

D2,856 S 12/1867 Stafford
D17,746 S 9/1887 Mellinger

FIG. 1 is a perspective view of an embodiment of a label sheet layout assembly showing our new design;

FIG. 2 is a front view thereof;

FIG. 3 is a back view thereof;

FIG. 4 is a first side view thereof;

FIG. 5 is a second side view thereof;

FIG. 6 is a top view thereof; and,

FIG. 7 is a bottom view thereof.

The broken lines in the figures are included for the purpose of illustrating portions of a label sheet assembly and do not form a part of the claimed design. The first side, second side, top, and bottom views include a shape and appearance that would be evident from the views of the label sheet assembly as shown.
